179,194

ATOMIZER

Karl Flury, Adliswil, Zurich, Switzerland, assignor to Defensor Aktiengesellschaft, Zurich, Switzerland, a corporation of Switzerland

Application September 9, 1955, Serial No. 37,866

Claims priority, application Switzerland April 4, 1955

Term of patent 7 years

(Cl. D83—1)

Fig. 1 is a perspective view looking downwardly on the atomizer at an angle to horizontal of about 45°

Fig. 2 is a top plan view of the atomizer, and

Fig. 3 is a side elevational view of the atomizer.

I claim:

The ornamental design for an atomizer, as shown.

References Cited in the file of this patent

UNITED STATES PATENTS

D. 155,031 Patterson _____ Aug. 30, 1949

OTHER REFERENCES

Aloe & Company Catalog No. 179, © 1946, page 282, lower left, Murphy Anastomosis Buttons.